UNITED STATES PATENT OFFICE.

ALPHONSUS L. GOLDEN, OF OAKLAND, CALIFORNIA, ASSIGNOR TO NATIONAL RADIO COMPANY, OF SAN FRANCISCO, CALIFORNIA, A CORPORATION OF ARIZONA.

OSCILLATOR.

Application filed May 16, 1917, Serial No. 168,957. Renewed August 9, 1922. Serial No. 530,810.

To all whom it may concern:

Be it known that I, ALPHONSUS L. GOLDEN, a citizen of the United States, residing at Oakland, in the county of Alameda and State of California, have invented new and useful Improvements in Oscillators, of which the following is a specification.

This invention relates to an oscillator for the production of high frequency oscillating currents for use in connection with radio telephones, telegraphs and the like.

One of the objects of the present invention is to provide a simple, compact, easily operated and adjusted oscillator for use in connection with apparatus producing high frequency oscillating currents, which apparatus is greatly reduced in size and weight and which only requires one pair of electrodes to produce the same amount of smooth, uniform, high frequency oscillations formerly only produced by oscillators employing several pairs of electrodes.

Other objects of the invention will be as follows:

25 To employ metal electrodes submerged in distilled water or a like liquid which is not inflammable or explosive in any way, which will not produce objectionable fumes nor deteriorate with use as is the case where alcohol is employed.

Using a spark gap where the electrodes are very close together to allow the condenser discharges to pass between the electrodes without creating too much heat, or, in other words, wasting energy in the form of heat in the surrounding liquid as well as in the electrodes.

To employ electrodes which permit the vapor or gases formed to freely discharge and furthermore to connect the oscillator in such a manner that it may either be used in connection with a telephone or a telegraph and be connected in a circuit employing either direct or alternating current.

45. Further objects will hereinafter appear.

The invention consists of the parts and the combination and arrangement of parts as hereinafter more fully described and claimed, having reference to the accompanying drawings, in which—

Fig. 1 is a diagrammatic view showing the different apparatus employed in the wireless telephone system.

Fig. 2 is a diagrammatic view showing 55 a wireless system capable of employing

either direct or alternating current and adapted to be used either as a wireless telephone or telegraph.

Fig. 3 is a central, vertical, longitudinal section through the oscillator.

Referring to the drawings in detail, and

Referring to the drawings in detail, and particularly to Fig. 1, I have shown the connection of the oscillator forming the subject matter of the present invention with the several other apparatus required in a wireless telephone sending and receiving station, in which A indicates a direct current generator connected in series with a solenoid magnet B; C indicates a pair of impedance coils, D a variable resistance and E an oscillator comprising a pair of submerged electrodes. This part of the station completes the direct current supply circuit while the primary oscillator circuit passes through a condenser F which is connected in series with the primary coil G of a high frequency transformer connected across the terminals of the electrodes forming the spark gap of the oscillator. The primary oscillator circuit is here shown in heavy lines to distinguish it from the current supply circuit in which the solenoid magnet is placed. The secondary oscillator circuit consists of the secondary coil of the transformer I, the antennæ H and the transmitter J which is connected, as shown at K, with the ground. 65 70 75 80 85

The several apparatus employed and the specific connections made do not form any important feature of the present invention, as these may be changed to suit varying conditions and requirements, and as the construction of the oscillator is the most important feature of the present invention it will readily be seen that the circuit connections are only of minor importance and are merely shown to illustrate one of the uses of the oscillator. 90 95

The oscillator proper consists of a cylindrical container 2 provided with a cover 3, preferably constructed of insulating material upon which is mounted a solenoid magnet 4 of suitable construction. Extending through the spool of the magnet is a tube 5 constructed of brass or any other non-magnetic material and extending through said tube is a brass rod 6 upon which is secured the movable core 7 of the magnet. This core is preferably constructed of soft laminated iron and as it is secured upon the rod 6, it can readily be seen that the two will be 100 105 110

lifted in synchronism when the magnet is energized. Secured on the upper end of the rod is a piston head 8 and surrounding said piston head is a cylinder 9 which may be 5 partly filled with oil to permit a dash-pot action. Suitably secured on the lower end of the rod is a copper electrode 10, the outer face of which is screw-threaded, as at 11, to allow a free escape of vapor or gases generated during the operation of the oscillator.

Extending downwardly from the cover section 3 is a pair of rods 12, and forming a covering for said rods is a pair of insulating tubes 13. Secured on the lower end 15 of the rods is a bracket plate 14 and adjustably mounted in said bracket plate in direct alignment with the electrode 10 is a second copper electrode 15.

In actual practice, it is only necessary to 20 fill the container 2 with a sufficient amount of distilled water to submerge the electrodes 10 and 15. This water serves as a partial conductor and a resistance between the adjacent faces of the electrodes, and therefore 25 permits the formation of a spark discharge between the same which is constantly moving from one place to another, said movement being due to the heating of the water and liberation of vapor or gases created by 30 each spark discharge. The variable resistance thus created causes the spark to continuously travel from one point to another, in this manner permitting an even burning or wasting of the electrode faces. A coil 35 16 mounted within the container through which cool water is circulated maintains the temperature of the distilled water as low as may be desired, thereby preventing overheating of the oscillator or generation of 40 steam during operation.

The separation of the electrodes when a circuit is established through the electrodes is caused by the current flow through the solenoid magnet 4. This when energized 45 raises the core 7, thereby automatically lifting the upper electrode with relation to the stationary lower electrode 15, the actual spacing being determined by the resistance of the liquid medium in which the electrodes 50 are submerged as the spark discharge can only jump a certain gap without breaking the circuit, and as the solenoid magnet is directly connected in the circuit passing through the electrodes, it can readily be seen that the spacing between the same is 55 automatically maintained by the solenoid.

In actual practice, it has been found that 60 copper electrodes can be most successfully employed in connection with distilled water, and it has also been found that the actual spacing required between the faces of the electrodes seldom exceeds three-thousandths of an inch. This is of great importance as 65 it permits the condenser discharges to pass between the electrodes without producing

wasted energy in the form of heat in the surrounding liquid or in the electrodes. A lower voltage can furthermore be employed in this type of oscillator as the spark gap is shorter, thereby allowing the condenser 70 discharge to pass through the distilled water film between the electrodes without having to pierce a gap having a higher resistance or requiring a heavier condenser discharge. A large gap requires a higher voltage to break 75 down the insulating properties of the liquid between the electrodes to produce the necessary path for the flow of the current. This necessity is entirely eliminated as a three-thousandths of an inch spark gap 80 has a comparatively small resistance, even though a film of distilled water is maintained between the electrodes.

The screw-thread formation 11 formed on the outside of the upper electrode is also an 85 important feature, as it permits any vapor or gases generated to freely discharge in an upward direction.

The action taking place at the spark gap is as follows: When the electrodes are separated a certain distance, there is a partial insulating film of distilled water formed between them. This film of water is pierced by the discharge from the condenser when the voltage of the circuit has reached its 90 highest point. The condenser discharge passing between the electrodes instantly vaporizes the water at the point of the discharge, thereby producing a higher resistance to the flow of the current than exists at 95 other points between the electrode faces. The higher resistance thus produced causes the flow of current through the oscillator circuit to be impeded at that point, thereby forcing the succeeding oscillations or discharges to pass between the electrodes at other points on their faces through the distilled water film which exists at all points, in this manner causing an even burning or wasting away of the electrodes during actual 100 operation.

In actual practice, it has been found that one pair of electrodes employed in the manner described produces a smoother and more uniform series of oscillations at a higher 115 rate of efficiency than has heretofore been produced by six pairs of electrodes submerged in alcohol. In the operation of a number of high frequency oscillators, it has been found that in order to produce uniform, persistent, undamped oscillations of high frequency, force and effect, it was absolutely necessary that the electrodes in each oscillator should be provided with separate or independent elements for the purpose of 120 adjusting the spacing between the electrodes in each separate oscillator. The importance of this feature can readily be understood, as a variation in spacing would render it practically impossible to produce synchronism of 130

oscillation between the several oscillators in a circuit. This one feature has caused a large amount of trouble where a number of oscillators are employed in series, and, as 5 the present form of oscillator is capable of producing the same result with only one pair of electrodes, it can readily be seen that this difficulty has been entirely overcome.

Another important feature is the employment of distilled water as it is not explosive, combustible nor does it deteriorate with use or produce objectionable odors when operating. These features all have to be contended with when alcohol is employed.

10 The apparatus as a whole may be greatly reduced in weight, size, cost of upkeep and cost of manufacture, not only because one pair of electrodes is employed, but also due to the simplicity of the construction. The 15 distilled water remains constant, that is, it seems as if it never loses its pressure conduction quality nor its insulating properties. It therefore serves its purpose more efficiently and continuously than alcohol, and 20 as it is cheap compared with alcohol, it is 25 certainly to be preferred.

While the diagrammatic view illustrated in Fig. 1 shows the oscillator employed in connection with a radio sending and receiving station, I wish it understood that it may also be used in connection with radio telegraphy or otherwise. For instance, by referring to the diagrammatic view shown in Fig. 2, it is possible to employ a direct current generator, such as shown at A and an alternating current generator, such as shown at 30. These generators may be connected with the primary circuit by a double-pole double-throw switch 31. Similarly the current circuit of the antennæ may be provided with a double-throw switch 32 which permits the secondary oscillation circuit to pass either through the transmitter or a key instrument, such as shown at 33. The station 35 may therefore employ a direct current when the phone is being employed or in connection with the key instrument or an alternating current may be employed in connection with the key instrument. The change 40 from phone to telegraphic service is practically instantaneous as it is only necessary to operate the switches 31 and 32 to change the current flow through the different instruments employed.

50 The material and finish of the several parts may be such as the experience and judgment of the manufacture will dictate.

I wish it understood that various changes

in the form, proportions and minor details of construction may be resorted to within 60 the scope of the appended claims, and that I do not wish to limit myself to the specific design and construction here shown.

Having thus described my invention, what I claim and desire to secure by Letters 65 Patent is:

1. An oscillator comprising a container a body of distilled water in said container, a stationary copper electrode mounted in the container, a movable copper electrode mounted in alignment with the stationary electrode, said electrode being entirely submerged in the distilled water, a screw thread formed on the exterior of the movable electrode and extending substantially 70 from end to end thereof, and means for automatically lifting the movable electrode and supporting it in spaced position with relation to the stationary electrode when a circuit is closed through the electrodes. 80

2. An oscillator comprising a cylindrical container, a body of distilled water in said container, a cover for the container, a pair of rods secured to the cover extending down into the container, a bracket plate connecting the lower ends of the rods, a copper electrode adjustably secured in said plate, an insulating covering for each rod, a solenoid magnet supported by the cover, a movable core in the magnet, a dash pot connected 90 with the upper end of the core, a rod secured to the opposite end of the core, a copper electrode carried by the rod and positioned in alignment with the first-named electrode, and an insulating covering for said rod. 95

3. In an oscillator, a container, distilled water in said container, a pair of vertically positioned equidistantly interspaced electrodes, submerged in the distilled water, and a screw thread formed on the exterior 100 surface of one of the electrodes and extending from top to bottom thereof.

4. In an oscillator a container, distilled water in said container, a pair of super-imposed electrodes submerged in the distilled 105 water, and a screw thread formed on the exterior surface of the upper electrode and extending to the plane of the sparking surface.

In testimony whereof I have hereunto set 110 my hand in the presence of two subscribing witnesses.

ALPHONSUS L. GOLDEN.
